SEWING MACHINE

Joseph Gouldbourn and Thomas Aubrey Kestell,
Leicester, England, assignors to United Shoe
Machinery Corporation, Paterson, N. J., a cor-
poration of New Jersey

Application August 23, 1932, Serial No. 630,044
In Great Britain September 29, 1931

15 Claims. (Cl. 112—38)

This invention relates especially to sewing machine shuttles and the driving thereof and is particularly, but by no means exclusively, concerned with rotary shuttles for lockstitch shoe outsole sewing machines, examples of which are disclosed in the U. S. patent to French and Meyer No. 473,870 granted April 26, 1892 and in the specification of British Letters Patent No. 23,478 of 1910. The present invention provides novel shuttle constructions which may conveniently be incorporated in a shoe outsole sewing machine in conjunction with thread handling mechanism such as is disclosed in the specification of British Letters Patent No. 357,596 the complete specification of which was accepted September 28, 1931 and/or in conjunction with a rotary take-up mechanism such as is disclosed in the specifications of applications for British Letters Patent Nos. 22,753 and 35,037 of 1931.

The present invention has among its several objects to ensure in a machine of the kind described in said British specification No. 23,478/10 an easy spreading of the loop of thread as it is passing along the beak of the shuttle, a free passage of the loop round the shuttle without twisting the loop, an easy threading of the bobbin case and uniform tensioning of the shuttle thread as it leaves the bobbin case without unduly flattening the thread.

The above and other objects and the several features of the invention will become apparent to those skilled in the art from a consideration of the following description, given by way of example and with reference to the accompanying drawings.

In the drawings:

Figure 1 is a front elevation of one form of shuttle, its driving means and a work support and needle of an outsole shoe sewing machine 40 which, except as otherwise indicated, will be assumed to be generally as described in said British Specification No. 23,478 of 1910;

Figure 2 is a right-hand side elevation of the shuttle mechanism and sewing machine parts 45 shown in Figure 1;

Figure 3 is a section on the line 3—3 in Figure 1 showing a section of the shuttle casing and its support;

Figure 4 is a rear elevation of a bobbin case, 50 associated with the form of shuttle shown in Figures 1, 2, and 3;

Figure 5 is a plan view of the bobbin case shown in Figure 4;

Figure 6 is a right-hand side elevation of said 55 bobbin case;

Figure 7 is a front elevation of a second form of shuttle and its driving means;

Figure 8 is a front elevation on a reduced scale of the shuttle shown in Figure 7 and means for limiting rotary movement of a bobbin case associated therewith; 5

Figure 9 is a section on the line 9—9 in Figure 7;

Figure 10 is a right-hand side elevation, partly in section of the said second form of shuttle; 10

Figure 11 is a side elevation, partly in section, of mechanism for moving the said means for limiting rotary movement of the bobbin case into or out of operative position;

Figure 12 illustrates the parts shown in Figure 15 11 in a different position;

Figure 13 is a front elevation, partly in section, of the said bobbin case;

Figure 14 is a left-hand side elevation of the 20 said bobbin case;

Figure 15 is an elevation of the said bobbin case viewed in the direction of the arrow in Figure 13;

Figure 16 is a perspective view of a portion of the bobbin case shown in Figures 13, 14 and 15, 25 illustrating the thread tensioning slide;

Figure 17 is a sectional view of a portion of the bobbin case, shown in Figure 4, taken along the line 17—17 of that figure; and

Figure 18 is a sectional view taken on the line 30 18—18 of Figure 17.

The form of shuttle illustrated in Figures 1 to 6 of the drawings comprises a shuttle casing 1 composed of two parts 2 and 3 fixed together and having formed between them an undercut 35

guideway 4 which receives a flanged guide 5 formed on a plate 6 fixed to a shuttle-carrying bracket 7 fixed on the machine frame. The plate 6 may, for purposes of assembly, be formed in three separate pieces. The shuttle casing 1 has 40 formed on it a beak 8, part of which is formed on each of the parts 2 and 3 of the shuttle casing 1 and its tip is so angled (as shown in Figure 2) that when the beak enters the loop of needle thread its edge 9, 9 and inner face 10 (see Figure 1) are substantially parallel to the length of thread 11 extending from the hook of the needle 12 to the thread lifter, a section of which is shown at 113 and the beak engages the greater part of this length of thread when it takes the loop of 50 needle thread from the needle and thread lifter. By reason of this comparatively wide beak the loop of needle thread slips readily along the beak and is easily spread sufficiently to allow the loop to pass over the shuttle casing. The wide beak 55

may be much shorter than one which as commonly used comes to a sharp point and because of this shorter beak, time may be saved in passing the loop over the shuttle casing, which saved time 5 may be used in allowing more time for other parts of the machine to operate in the working cycle of the machine. The passage of the loop of needle thread along the inner face 10 of the beak down to its root 210 is ensured by the round end 10 116 of the plate 6 which, if the loop does not itself slip along the beak as the shuttle casing rotates, engages the loop and actually pushes it along the said inner face 10 of the beak.

The shuttle casing 1 is driven by a driving 15 member 13 extending from a disc 14 fixed to a gear 15 rotatably mounted in the bracket 7. The gear 15 is driven by a gear 16 having extending from it a shaft 17, rotatably mounted in the bracket 7, and having fixed to it a disc 18 which 20 has fixed in it a crank-pin 19. The crank pin 19 has pivoted on it one end of a link 20, the other end of which is pivoted on a crank-pin 21 fixed in a crank-arm 22. The crank-arm 22 has extending from it a shaft 23 rotatably mounted in 25 the machine frame and driven in any suitable manner from the driving shaft of the machine. The shaft 23 is driven at such a speed that the shuttle makes two revolutions in each cycle of the machine and the relatively offset shafts 17, 23 30 crank pins 19, 21 and link 20 are so arranged that the speed of the shuttle casing 1 is increased as the loop of needle thread is passed over the shuttle casing so that it then travels at a speed equal to about three revolutions of the shuttle casing in 35 each cycle of the machine. The speeding up of the shuttle casing as above described ensures a rapid passage of the needle thread over the shuttle casing, thereby allowing more time in the cycle of the machine for other parts to function and 40 allows the speed of the machine to be increased without unduly increasing the shuttle speed (with consequent risk of wear) throughout the cycle. The slowing down of the shuttle-casing driving member 13 occurs after the needle loop has passed 45 over the top of the shuttle casing and results in the shuttle casing 1 by reason of its momentum over-running the driving member until the bottom part or root 210 of the beak 8 engages the end 24 of the driving member 13. A gap is then 50 momentarily left between the end 25 of the driving member 13 and the face 26 on the shuttle casing through which gap the needle loop passes quite freely as it is pulled down by the take-up of the machine.

55 The bobbin case 30, shown in Figures 4, 5, and 6, has formed in it a stem 31 on which the bobbin 32 is rotatably mounted. The bobbin case has in it a hole 33 through which the thread passes from the bobbin and this hole is so positioned in the bobbin case as to give the best lead 60 of the thread from the bobbin to the hole irrespective of whether the diameter of the coils of thread on the bobbin is large or small, or whether the thread is being drawn from one end or the other of the bobbin. The bobbin thread passes from the hole 33 along a groove 34 formed in the bobbin case and in this groove is slidingly mounted a block 35 having projecting upwardly from it a guide pin 36 which enters a guide recess 37 in 65 the bobbin case. A spring 38 urges the block 35 towards the bottom of the groove 34 and causes the block to exert a tension on the bobbin thread. The groove 34 is only just large enough to receive the bobbin thread and between the inner end of 70 75 the block 35 and the bottom of the groove 34

there is, in effect, formed a hole through which the thread passes and this hole prevents the thread from being unduly distorted by the pressure of the block 35. The pressure of the block 35 against the thread may be adjusted by moving the legs 39, 39 of the spring inwardly or outwardly in their holes 40, 40 in the bobbin case. The legs 39, 39 are slightly bent so that when pushed into the holes 40, 40 they bind on the sides of the holes and are thus held in adjusted position. After 10 passing along the groove 34 the bobbin thread passes through a hole 41 in the bobbin case and emerges from the front wall 42 of the bobbin case. The bobbin case 30 is carried in a recess 43 in the shuttle casing 1 and is rotatably mounted on a pin 44 extending from the part 3 of the shuttle casing and entering a bore in the stem 31. The axis of the recess 43 and pin 44 is offset about three-thirty-seconds of an inch from the 15 axis of the shuttle casing.

Rotary movement of the bobbin case 30 is limited by the engagement of a conical projection 45 on the bobbin case with one side or the other of a recess 46 in an arm 47 which is fixed to a stud 48 pivoted in a lug 49 projecting from 20 the bracket 7. Also fixed to the stud 48 is a hand lever 50 by which the arm 47 may be swung away from in front of the shuttle casing to allow the bobbin case to be withdrawn. The rotation of the shuttle casing 1 tends, through the friction 25 between the pin 44 and the stem 31 of the bobbin case 30, to rotate the bobbin case in the same direction as the shuttle. This tendency keeps the length of thread between the hole 41 in the bobbin case and the work more or less taut. 30 This, owing to the friction device 35, in effect anchors that part of the bobbin case 30 in which is the hole 41 and as the shuttle casing 1 rotates, the projection 45 is, by reason of the eccentricity 35 of the pin 44, moved in substantially an elliptical 40 path. The arrangement is such that when the loop of needle thread is being pulled down past the projection 45, the projection is about midway between the sides of the recess 46 and the loop of needle thread has a perfectly clear passage between the projection 45 and arm 47. When the stitch is being set and thread is being pulled from the bobbin, the projection 45 is pulled up by the pull on the shuttle thread against the upper side 45 of the recess 46. The lower wall of the recess 46 is not engaged by the projection 45 during rotation of the shuttle casing and only acts in generally positioning the bobbin case when the machine is at rest or if the thread should break. 50 The arm 47 has fixed to it a clip 51 behind which the loose end of the shuttle thread may be placed after a length of sewing has been completed and the threads cut off, and anchored while the first stitch or first few stitches of a fresh length of sewing are made. An adjustable screw 52 is threaded through the arm 47 and engages the plate 6 to position the arm 47 in relation to the projection 45, it being understood that suitable latching means is provided for holding the arm 47 in adjusted position.

The said second form of shuttle shown in Figures 7 to 16 of the accompanying drawings comprises a shuttle casing 60 composed of two parts 61 and 62 fixed together and formed with an undercut guideway 63 between them, which 70 receives a flanged guide 64 formed on a plate 65 fixed to a shuttle carrying bracket 66 fixed to the machine frame. The plate 65 may be made in three parts, for purposes of assembly, if desired. The shuttle casing 60 has formed on it a beak 67, 75

67 part of which is formed on each part 61 and 62. The beak 67, 67 is similar in shape and action in taking the loop of needle thread from the needle and the thread lifter to the beak 8 in the first form of shuttle described above. The rounded end 68 of the plate 65 likewise ensures that the loop of needle thread shall pass down the inner face 69 of the beak to its root.

The shuttle casing 60 is driven by a driving member 70 extending from a disc 71 formed on the end of a shaft 72 rotatably mounted in the bracket 66 and in the machine frame. The shaft 72 has fixed on it towards its rear end a crank-arm 73 (Figure 7) carrying a crank-pin 74 on which is pivoted one end of a link 75, the other end of which is pivoted on a pin 76 carried by an arm 77 fixed on a shaft 78 rotatably mounted in the machine frame and driven by any suitable means from the driving shaft of the machine.

20 The shaft 78 is driven at such a speed that the shuttle casing 60 makes two revolutions in each cycle of the machine and the relatively offset shafts 72, 78 crank pins 74, 76 and link 75 are arranged in a similar manner and for the same purpose as the corresponding parts in the first form of shuttle and its driving mechanism hereinbefore described.

The bobbin case 80 of the second form of shuttle shown in Figures 13, 14 and 15 has in it a stem 81 on which the bobbin is rotatably mounted. The stem 81 and recess in the bobbin case are, as in the earlier described construction, eccentric to the outer wall of the bobbin case so as to leave a thickened wall at one side of the bobbin case. The thread from the bobbin passes through a hole 82 in the bobbin case and then round a rounded corner 83 beneath a ledge 84 and along a groove 85. The groove 85 leads to a hole 86 in a nose 87 formed on the bobbin case out of which the thread passes. The hole 82 is positioned in the bobbin case 80 so as to give the best lead of the thread from the bobbin to the hole irrespective of whether the thread is being drawn from one end or the other of the bobbin or whether the diameter of the thread on the bobbin is large or small and the rounded corner 83 and guideway provide a passage for the thread which is as free as possible from sharp bends. The nose 87 delivers the thread beyond the path of movement of the beak 67, 67 of the shuttle and as close as is convenient to the work. The shuttle thread is thus well controlled and the possibility of the position of the shuttle thread passing between the shuttle and the work becoming caught by the beak or becoming cold if the shuttle is heated and a waxed thread is being used is minimized.

The shuttle thread as it passes along the groove 85 on the bobbin case 80 is tensioned by the end 60 of a slide 106, mounted in a guideway formed in the bobbin case 80. The end of the slide 106 where it engages the thread extends partly over the thread and with the groove 85 forms practically a hole through which the thread passes. The thread is in this way prevented from being unduly flattened by the pressure of the slide 106. The slide is urged towards the thread by a spring 107, the legs of which enter holes 108, 108 in the case. The legs of the spring are curved slightly 65 so that they tend to bind in the holes and their position along the holes may be varied to vary the pressure of the spring. Two other holes 109, 109 are provided so that a shorter and stiffer spring may be used if desired.

75 Rotary movement of the bobbin case 80, which

freely enters a recess in the shuttle casing 60 and is mounted on a pin 88 of comparatively small diameter extending from the inner face of the part 62 of the shuttle casing 60, is limited by a V-shaped ridge 89 (Figure 10) formed on a member 90, which V-shaped portion enters a V-shaped groove 91 (Figures 13 and 15) formed in the front wall of the bobbin case 80. The pin 88 is coaxial with the recess in the shuttle casing and with the axis of the shuttle casing. The member 90 is fixed to an arm 111 fixed to a shaft 92 rotatably mounted in bearings 93, 93 on the shuttle carrying bracket 66. The shaft 92 has formed on one end of it an arm 94 and a member 95 which are of the shape illustrated in Figures 11 and 12. Also rotatably mounted in the shuttle carrying bracket 66 is a shaft 96 which has fixed on it a hand-lever 97 by which it may be rotated and also has formed on it a disc 98 having formed in it a recess 99 (Figure 11) and having its periphery 100 slightly eccentric to the axis of the shaft 96. The disc 98 has projecting from it two pins 101 and 102. When the parts are in the position they occupy in Figure 11 the member 90 is held in its operative position by the engagement of the eccentric periphery 100 of the disc 98 with the arm 94 which presses an adjustable screw 103 threaded through a lug 104 projecting from the arm 111 against the plate 65. If, from the position shown in Figure 11, the hand-lever 97 is swung in an anti-clockwise direction the locking action of the periphery 100 and arm 94 is first released, then the pin 101 engages a curved part 104 of the member 95 and through the member rotates the shaft 92 and swings the member 90 upwardly away from the bobbin case 80. The pin 101 rotates the member 95 until the rounded end 105 of the arm 94 and the recess 99 in the disc 98 engage and continue the rotation of the shaft 92 until the hand-lever 97 engages one of the bearings 93 when the parts are in the position shown in Figure 12. In this position the member 90 is raised so that the bobbin case 80 can be withdrawn from the shuttle casing 60, and is held in this position by the engagement of the arm 94 with the periphery of the disc 98. As the hand-lever 97 is returned to the position shown in Figure 11 the member 90 either swings down to its operative position by its own weight or is moved down by the pin 102 engaging the curved part 106 of the member 95 and by the rounded end 105 of the arm 94 and recess 99, and is locked in operative position by the engagement of the eccentric periphery 100 of the disc 98 with the arm 94. The V-shaped projection 89 on the member 90 and the groove 91 in the bobbin case 80 are so arranged that as the loop of needle thread passes over the top of the bobbin case the length of thread which passes between the V-shaped projection and groove is substantially parallel to the groove and moves across the axis of the pin 88 at substantially right angles to the length of the groove and is, therefore, moving in the most favourable direction to separate the projection and groove if these are in contact. The friction between the pin 88 and the bore in the bobbin case 80 tends to turn the bobbin case in an anti-clockwise direction (viewed from the front) but this tendency is to a certain extent overcome by the weight of the nose 87 and there is little resistance to the passage of the needle thread between the projection 89 and groove 91.

Fixed on the member 90 is a guard 110. This guard is substantially of the shape shown in

75

Figures 8 and 10 and is arranged to guide the loop of needle thread as it is pulled down after passing over the bobbin case towards the shuttle thread where it extends upwardly from the work and to prevent the loop of needle thread from being caught on a projecting portion of the work or, for instance, on a tack projecting from the work and being prevented thereby from being pulled into the work.

10 Having now particularly described the nature of the present invention, what is claimed is:

1. A lockstitch sewing machine having, in combination, a hook needle, a rotary shuttle having a wide loop taking beak formed with a substantially flat inner face inclined at an angle to the rotary axis of the shuttle and a loop spreader acting when a loop of thread is drawn through the work by the needle to separate one side of the loop from the other side and to position a portion of the thread in parallel relation to the said inner face as the beak engages the thread.

2. A lockstitch sewing machine having, in combination, a hook needle, a loop spreader acting when a loop of thread is drawn through the work by the needle to separate one side of the loop from the other side, and a rotary shuttle having a loop taking beak of such width at its end that as the beak enters a loop of needle thread it engages the greater part of the length of thread extending between the loop spreader and the needle.

3. A lockstitch sewing machine having, in combination, a hook needle, a loop spreader acting when a loop of thread is drawn through the work by the needle to separate one side of the loop from the other side, and a shuttle comprising a rotary shuttle casing formed with a circular guideway about its outer edge and a beak having a wide loop taking end, a part of the beak end being formed on either side of the guideway.

4. A lockstitch sewing machine having, in combination, a hook needle, a loop spreader acting when a loop of thread is drawn through the work by the needle to separate one side of the loop from the other side, a shuttle comprising a rotary shuttle casing formed in two parts fixed together, each part having formed on it a grooved portion comprising a circular guideway and a flanged circular shuttle guide in engagement with the guideway.

5. A lockstitch sewing machine having, in combination, a hook needle, a loop spreader acting when a loop of thread is drawn through the work by the needle to separate one side of the loop from the other side, a shuttle comprising a rotary shuttle casing formed with a circular guideway about its outer edge and a beak having a wide loop taking edge, a part of the beak edge being formed on either side of the guideway and a circular shuttle guide engaging the guideway, formed with a portion at one end for pushing the loop of thread away from the edge of the beak towards the center of the shuttle as the shuttle casing revolves.

6. A lockstitch sewing machine having in combination, stitch-forming devices including a hook needle and a rotary shuttle having a loop taking beak, a thread case mounted in the shuttle to turn about an axis eccentric to the center of shuttle rotation, said thread case having a thread passage at one side of the thread case axis, friction means for resisting withdrawal of shuttle thread from the thread case, a stationary stop for preventing rotation of the thread case, the arrangement of the thread case and the shuttle

beak being such that the thread case will be rotated away from the stationary stop as the needle thread passes between the two due to increasing tension on the shuttle thread extending between the thread case and the work.

7. A lockstitch sewing machine having, in combination, stitch forming devices including a hook needle, a rotary shuttle having a loop taking beak, a thread case mounted in the shuttle to turn relatively to the shuttle, and means for maintaining the thread case against turning movement comprising inter-engaging portions on the thread case and a stationary part in the form of a groove and a cooperating ridge, so arranged that when a loop of needle thread is being passed over the thread case the length of thread passing between the groove and ridge portions moves in a direction substantially at right angles to the length of the groove portion.

8. A lockstitch sewing machine having, in combination, stitch forming devices including a hook needle, a rotary shuttle having a loop taking beak, a thread case mounted in the shuttle to turn relatively to the shuttle, and means for maintaining the thread case against turning movement comprising a radial groove portion in the thread case and a cooperating ridge portion on a stationary part, so arranged that when a loop of needle thread is being passed over the thread case the length of thread passing between the groove and ridge portions moves in a direction substantially at right angles to the length of the groove portion.

9. A lockstitch sewing machine having, in combination, stitch forming devices including a hook needle, a rotary shuttle having a loop taking beak, a thread case mounted in the shuttle and formed with an elongated nose which engages and delivers the shuttle thread beyond the path of movement of the shuttle beak.

10. A lockstitch sewing machine having, in combination, stitch forming devices including a hook needle, a rotary shuttle having a loop taking beak, a thread case mounted in the shuttle having a passage for conducting thread toward the work and a movable thread tension member in the passage forming with the casing substantially a hole through which the thread passes.

11. A lockstitch sewing machine having, in combination, stitch forming devices including a hook needle, a rotary shuttle having a loop taking beak, a thread case mounted in the shuttle, and a guard for directing the loop of needle thread to the shuttle thread where it extends from the work to the thread case.

12. A lockstitch sewing machine having, in combination, stitch forming devices including a hook needle, a rotary shuttle having a loop taking beak, a thread case mounted in the shuttle, and means loosely engaging the shuttle for driving it at a high speed while the beak of the shuttle carries the needle thread and at a comparatively low speed in the same direction during the remaining part of its movement, the needle thread being passed between the driving means and the shuttle at the time in which the driving means is slowing down from high to low speeds to permit the shuttle to run ahead of the driving means and provide a clearance space therebetween.

13. A lockstitch sewing machine having, in combination, stitch forming devices including a hook needle, a rotary shuttle having a recess at one side and a loop taking beak extending from one end of the recess, a thread case mounted

in the shuttle, and means loosely engaging the shuttle within said recess for driving it at a high speed while the beak of the shuttle carries the needle thread and at a comparatively low speed in the same direction during the remaining part of its complete cycle of movement, the needle thread being passed between the beak end of the shuttle recess and the driving means at the time in which the driving means increases its movement from low to high speeds and the thread being passed between the other end of the shuttle recess and the driving means at the time in which the driving means is slowing down to provide clearance spaces between the driving means and the shuttle at the respective times of thread passage.

14. A lockstitch sewing machine having, in combination, stitch forming devices including a hook needle, a rotary shuttle, a thread case mounted in the shuttle and a thread tension in the thread case comprising a friction member

movable against the thread and a U-shaped spring element, the U-part of which is bent out of the plane of the ends and engages the thread tension member to move it against the thread, said ends being slidably disposed in holes formed in the thread case substantially parallel to the direction of movement of the tension member and maintained adjustably in position therein by frictional engagement.

15. A lockstitch sewing machine having, in combination, stitch forming devices including a hook needle, a rotary shuttle, a thread case mounted in the shuttle, a guard pivotally mounted on a stationary part of the machine and a pivoted handle movable continuously through an arc about its pivot for unlocking the guard from either operative or inoperative positions and moving the guard to the other of said positions and locking it in said other position.
